HOWARD M. FERREE, OF JERSEY CITY, NEW JERSEY, ASSIGNOR TO GENERAL ELECTRIC VAPOR LAMP COMPANY, OF HOBOKEN, NEW JERSEY, A CORPORATION OF NEW JERSEY

ILLUMINATED SIGN

Application filed April 30, 1930. Serial No. 448,478.

The present invention relates to electric signs, and particularly to signs in which an illuminated background is viewed through suitable openings in an opaque face.

The object of the present invention is to provide means whereby the background of such a sign may be uniformly illuminated by a linear source of light, such as a straight gaseous electric discharge tube. Another object of the invention is to provide means whereby said source of light may be made to simultaneously illuminate both sides of a suitable baffle, thereby providing the background for a sign which may be viewed from either side. Other objects and advantages of the invention will appear from the following detailed specification, or from an inspection of the accompanying drawings.

Although signs have heretofore been constructed in which an illuminated plane diffusing reflector or background was viewed through suitable perforations or openings in the face of the sign, these signs have not been entirely satisfactory, since for best results the light source had to be concealed from direct view, and hence was located outside of the perforated area. With such an arrangement it has been necessary to provide light sources on several edges of the perforated legend, since it is impossible to produce uniform illumination of the entire sign when a single linear light source, such as a high intensity electric gaseous discharge tube, was used. Furthermore, separate light sources have heretofore been required for each side of a sign of this type which was to be viewed from more than one direction.

I have discovered that by providing a reflecting background of novel construction not only may this difficulty be entirely overcome, but that a single linear light source may be made to provide uniform illumination for both sides of a sign which may thus be viewed from either direction. As a result a considerable economy may be effected in the production of this type of sign, since either fewer light sources, or a simpler form thereof may be used.

For the purpose of illustration I have shown a sign embodying a preferred form of

my invention, together with several variations thereof, in the accompanying drawings, in which

Fig. 1 is a front elevation, in part section, of a double faced sign with a preferred form of background or baffle, 55

Fig. 2 is an irregular sectional view taken on the line 2—2 of Fig. 1,

Fig. 3 is a similar sectional view to that of Fig. 2 of a sign having a modified form of baffle, 60

Fig. 4 is an elevational view of a face plate showing a modification in which a portion of the back thereof is painted black to aid in producing uniform illumination of the baffle. 65

In these drawings, with special reference to Figs. 1 and 2, the two face plates 1 are attached in a suitable manner to the flanged spacer 2 with which they cooperate to form a box which is substantially light tight, except for the apertures 3 which form the sign, said apertures being formed either in the face plates 1, or in interchangeable closures for suitable openings in said face plates. Two standard Cooper Hewitt gaseous discharge lamps 4 of the hot cathode type are shown mounted on the spacer 2 along a line midway between the face plates 1 and below the apertures 3, although it is obvious that a single light tube of longer length could be substituted therefor, if desired. A reflecting baffle, which is conveniently formed of the two similar metal sheets 5 is suitably supported above the lamps 4, with the lower edge thereof directly above said lamps. Each of said baffle plates 5 is curved upwardly and outwardly in a curve which is so designed that the entire baffle receives substantially uniform illumination from the lamps 4. Said baffle plates 5 are each coated on the side 90 toward the apertures 3 with a diffusing surface having the desired color characteristic, red being especially suitable, for instance, where neon is employed in the lamps, while the face plates 1, spacer 2 and other interior parts are either white or the same color as the baffle plates 5. The usual auxiliary apparatus for lamps of this type, including transformer, resistances, inductance, shifter, etc., is mounted in a casing 6 which is convenient- 95

ly located in the space above the baffle plates 5, and as shown in Figs. 2 and 3 this makes a very compact unit with all space therein utilized to advantage.

6 While the curvature of the surfaces of the baffle plates 5 which would be required for absolute uniformity of illumination would be very complex, and therefore difficult to construct, it has been found that a simple surface, approaching the form of a segment of a cylinder which would pass through the axis of the lamps 4, gives an approximation thereof which is entirely satisfactory for commercial purposes. In some cases an even more 15 simple form of baffle may be used with good results. As shown in Fig. 3 the metal sheets 5 comprising the baffle are each constructed with two plane surfaces, intersecting at a slight angle, so that they roughly approximate the continuously curved metal sheets 5 of Figs. 1 and 2. A somewhat marked contrast in illumination tends to develop at the intersection of the plane surfaces with this construction, which is overcome by suitable 20 reflectors 7 which are designed to direct light from the lamps 4 to that surface of the baffle which has the lower intensity of illumination near said intersection.

Some variation in the intensity of the 25 illumination of the baffle plates 5 adjacent to the ends of the lamps 4 is inevitable when simplified baffle surfaces such as have been described are used, but this variation is not ordinarily particularly noticeable. When desired, however, this effect may be largely overcome by painting a portion of the back of each face plate 1 black, the remainder being a good reflector. As shown in Fig. 4 the two areas 8, each of which is located adjacent to the central portion of a lamp 4 and near the bottom edge of a face plate 1 are thus painted in order to absorb light which would otherwise be reflected onto the baffle plate 5 back of the letters "C" and "E" where the intensity would otherwise be greater 40 than that on the remainder of the baffle. Reflectors may also be placed at the ends to redirect some of the light to points of lesser intensity.

50 Where it is necessary or desirable to protect the interior of the sign from the weather the apertures 3 may be closed with suitable transparent or opalescent glass sheets, as shown at 9 in Fig. 3.

55 In the use and operation of the device of Figs. 1 and 2, the lamps 4 being lighted in the usual manner, the light therefrom is divided evenly between the two sides of the sign. A considerable amount of this light 60 strikes the baffle plates 5 directly, causing a substantially uniform illumination thereof. The white interior of the sign, aided by a parabolic reflector below the lamps 4, where desired, also serves to reflect more of the light back onto said baffle, thus increasing

the intensity without markedly affecting the uniformity of the illumination. As a result the sign, when viewed from either side, presents a luminous legend of substantially uniform intensity. During the daylight hours 70 the sign is also effective since the background absorbs all the incident light save that of its characteristic color, which alone is reflected. In the modification of Fig. 3 substantially 75 the same result is produced, since the light reflected from the reflectors 7 assists in the production of a substantially uniform illumination on the reflecting baffle.

In the modification of Fig. 4, which may 80 be used with either of the foregoing structures, the black areas 8 reduce the intensity of the light on highly illuminated portions of the baffle to the intensity prevailing on the remainder of said baffle through reducing the light reflected to said portions. 85

While I have illustrated and described my invention in connection with a double faced sign using a definite type of light source, it is obvious that it is not limited thereto, and that various changes, omissions, and substitutions, within the scope of the appended claim, may be made in the illustrated structure without departing from the spirit of my invention.

95 I claim as my invention:

An illuminated sign comprising a substantially light tight box having apertures constituting a legend in the face thereof, a substantially linear light source within said box, and a diffusing reflector for said light source, said reflector being visible through said apertures, the inner surface of said face being a good reflector except for that portion thereof which is adjacent to the central part of said linear light source, said portion being a poor reflector, whereby the light reflected to said diffusing reflector from the inner surface of said box renders the illumination of said diffusing reflector more uniform.

100 Signed at Hoboken, in the county of Hudson and State of New Jersey, this 28th day of April, A. D. 1930.
